UNITED STATES PATENT OFFICE.

LORENZO GRISERI, OF NEW YORK, N. Y.

AUTOMATIC PIANO.

961,122.

Specification of Letters Patent. Patented June 14, 1910.

Application filed April 9, 1906. Serial No. 310,775.

To all whom it may concern:

Be it known that I, LORENZO GRISERI, a subject of the King of Italy, residing at New York, in the county and State of New York, 5 have invented a new and useful Improvement in Automatic Pianos, of which the following is a specification.

This invention relates to that class of mechanical or self-playing pianos which are 10 provided with means for effecting a rapid vibratory action of the hammers particularly those of the treble so as to produce the effect of a mandolin.

The object of my invention is the provision of a simple and inexpensive action of this kind.

In the accompanying drawings consisting of three sheets: Figure 1 is a sectional front elevation of a mechanical piano embodying 20 the improvement, showing only the hammers which constitute the mandolin section of the piano action. Fig. 2 is a fragmentary transverse section thereof showing one of the hammers in its inoperative position. 25 Fig. 3 is a similar view, on an enlarged scale, showing the hammer in its operative position.

Similar letters of reference indicate corresponding parts throughout the several 30 views.

A indicates a pin barrel arranged horizontally in the case B, and C the vertically swinging keys pivoted in the customary slotted supporting bar D.

35 e indicates the hammers of the mandolin action arranged above the keys C and each mounted at the upper end of an upright lever E pivoted near its lower end to a vertically swinging arm or lever F. The latter 40 is pivoted by a transverse pin f to a horizontal supporting bar G arranged in front of the strings H and made of the proper length to carry all of the levers F.

I is a spring connecting the front end of 45 the lever F with the supporting bar G and tending to elevate the rear end of said lever, and J is a similar spring connecting the lower arm of the hammer lever E with said supporting bar and tending to swing the 50 hammer rearwardly against the corresponding string, the last named spring being arranged underneath the lever F.

The rear end of the lever F is connected 55 with the rear end of the corresponding key C by a rod K, so that when the front end of the key is elevated by a pin of the rotary

barrel the lever F and the hammer-lever carried by it are depressed.

L is an actuating or vibrating device for 60 swinging the several hammer-levers in one direction preferably away from the strings. The device shown in the drawings consists of a rotary horizontal drum or cylinder arranged below the series of hammer-levers and having annular rows of trip-pins or 65 projections l one row for each lever. By the rapid rotation of the cylinder L in the direction of the arrow, these pins trip in quick succession over a metallic wear plate or tongue l¹ secured to the lower end of the lever, when the latter is lowered into the path of the pins by the actuation of the corresponding key C. While the hammer-lever is thus momentarily held in its depressed position, it is rapidly vibrated by the alternate 70 75 action of the trip pins and the spring J in an obvious manner, causing the hammer-head to strike the string numerous times for every note and producing a mandolin effect. When the raised key clears the pin of the 80 barrel, the spring I of the corresponding lever F raises the latter sufficiently to withdraw the companion hammer-lever out of the path of the trip-pins l, as shown in 85 Fig. 2.

The hammer actuating drum L may be 90 driven by any suitable means. In the construction shown in the drawings, the drum-shaft is driven from a shaft m arranged at right angles thereto, by a belt m¹ running around pulleys m² m³, the shaft m being in turn driven from the pin barrel by worm-gearing n, n¹. Suitable means are provided for limiting the upward stroke of the carrying-levers E. The devices shown in the 95 drawings consist of a series of buttons o arranged immediately above said levers and carried by vertical adjusting screws o¹ arranged in a fixed supporting bar P which extends across the series of levers. 100

The arrangement of the springs I on the front side of the supporting bar G facilitates the assemblage of the parts and the adjustment and renewal of the springs.

I claim as my invention:—

1. In a musical instrument of the character described, the combination of a support, a vertically-swinging carrying lever pivoted to said support, a hammer-lever pivoted to and carried by said carrying lever and extending below the same, a vibrating device arranged below the hammer-lever and hav-

ing projections adapted to swing said lever in one direction, a spring connected with the hammer-lever to swing the same in the opposite direction, a second spring connecting the carrying lever with said support and tending to hold its rear end in its elevated position, and means connected with the rear portion of said carrying lever for depressing the same, substantially as set forth.

2. In a musical instrument of the character described, the combination of a support, a vertically-swinging carrying lever pivoted to said support, a hammer-lever pivoted to and carried by said carrying lever, a vibrating device arranged below the hammer-lever and having projections adapted to swing

said lever in one direction, a spring arranged on the lower side of the carrying lever and connected with the hammer-lever to move the same in the other direction, a second spring connected with said carrying lever and normally holding its rear end in its elevated position, and means connected with the rear portion of the carrying lever for depressing the same, substantially as set forth.

Witness my hand this 19 day of March, 1906.

LORENZO GRISERI.
